US0D1066608S

(12) **United States Design Patent** (10) **Patent No.:** **US D1,066,608 S**
Reinhardt (45) **Date of Patent:** **** Mar. 11, 2025**

(54) **FLUID DISTRIBUTION EQUIPMENT**
(71) Applicant: **Neoperl GmbH**, Müllheim (DE)
(72) Inventor: **Holger Reinhardt**, March/Buchheim (DE)
(73) Assignee: **Neoperl GmbH**, Müllheim (DE)

(**) Term: **15 Years**

(21) Appl. No.: **35/518,702**

(22) Filed: **Aug. 23, 2023**

(80) **Hague Agreement Data**

Int. Filing Date: **Aug. 23, 2023**

Int. Reg. No.: **DM/232127**

Int. Reg. Date: **Aug. 23, 2023**

Int. Reg. Pub. Date: **Oct. 20, 2023**

(51) **LOC (15) Cl.** **23-01**
(52) **U.S. Cl.**

USPC **D23/266**

(58) **Field of Classification Search**

(57) **CLAIM**

The ornamental design for a fluid distribution equipment as shown and described.

DESCRIPTION

The patent or application file contains at least one drawing executed in color. Copies of this patent or patent application publication with color drawing(s) will be provided by the Office upon request and payment of the necessary fee.

1. Fluid distribution equipment

1.1 : Perspective view

1.2 : Side view

1.3 : State in use partial view

1.4 : Magnified view

The parts shown by means of yellow squares in the reproduction are not part of the claimed design.

1 Claim, 2 Drawing Sheets
(1 of 2 Drawing Sheet(s) Filed in Color)
